Leo Lion, New York, N. Y.

Application September 23, 1946, Serial No. 133,525

Term of patent 7 years

(Cl. D73—1)

To all whom it may concern:

Be it known that I, Leo Lion, a citizen of the United States of America, residing at New York, in the county of New York and State of New York, have invented a new, original, and ornamental Design for Personalized Birthday Candles, of which the following is a specification, reference being had to the accompanying drawing, forming part thereof.

Figure 1 is an elevational view of a personalized birthday candle partly broken away, showing my new design.

Fig. 2 shows a top view of the candle according to my new design.

I claim:

The ornamental design for a personalized birthday candle, as shown.

LEO LION.
